His Attorney.

UNITED STATES PATENT OFFICE.

HORACE J. SECOR, OF TOLEDO, OHIO, ASSIGNOR OF ONE-HALF TO JAMES A. TURNER, OF SAME PLACE.

BURIAL-CASKET.

SPECIFICATION forming part of Letters Patent No. 620,980, dated March 14, 1899.

Application filed September 30, 1898. Serial No. 692,271. (No model.)

To all whom it may concern:

Be it known that I, HORACE J. SECOR, a citizen of the United States, residing at Toledo, Lucas county, Ohio, have invented certain

5 new and useful Improvements in Burial-Caskets, of which the following is a specification.

My invention relates to a burial-casket having a separable top and bottom; and its object is to provide means for automatically, hermetically, and permanently sealing the casket.

15 Heretofore burial-caskets designed to be hermetically and automatically sealed have proved unsatisfactory owing to the great length and surface of the joints to be closed. It is found that such joints can be made airtight and water-tight only by the use of manually-operated clamping devices.

20 A further object of my invention is to overcome the objections here pointed out, and more particularly to provide a casket in which the vertical portion, the bottom, and lid may be hermetically sealed together manually and in which the final hermetic sealing is effected 25 by means of a panel in the lid of the casket adapted to be automatically and inaccessibly locked and sealed in place.

I obtain these objects by means of the devices and arrangement of parts hereinafter 30 described, and illustrated in the accompanying drawings, made part hereof, in which—

Figure 1 is an end view of my casket closed; Fig. 2, a central vertical cross-section of the same; Fig. 3, a top plan view of the bottom 35 plate of the lid-panel hereinafter referred to; Fig. 4, a central vertical longitudinal sectional elevation of the lower part of the casket, showing the elevating-board in operative position; Fig. 5, a top plan view of one 40 end of the casket with the lid removed, it being understood that both ends are substantially alike; Fig. 6, an enlarged vertical sectional elevation of the angle formed by the meeting bottom and side or end of the casket, taken centrally of either of the hinges 7 8, hereinafter referred to; and Fig. 7, a front elevation of the same.

Like reference-numerals indicate like parts throughout the drawings.

50 In the drawings, 1 indicates the sides and

ends of the casket, consisting in the example shown of a single strip of sheet metal shaped over a former and having its meeting ends brazed at one of the corners.

2 is the bottom of the casket, preferably 55 having at its margins a continuous upturned flange 3, into which the bottom of piece 1 exactly fits.

The top of the casket consists of three parts—viz., the marginal part 4, which rests 60 upon and engages the upper margin of the piece 1, the cove-piece 5, having its outer margin secured to the inner margin of piece 4 and being provided with an inwardly-projecting horizontal flange 5^a, and the panel 65 6, resting removably upon the flange 5^a and being adapted to be locked thereto. A series of hinges is secured in the inner angle of the parts 1 and 2, the hinge-leaves 7 being secured to the bottom of the casket, the 70 leaves 8 being free to swing against and parallel with the inner side of part 1. There is a hole 8^a through each of the leaves 8, adapted when the leaf is pressed against the side of the casket to receive the head of the axially-revolvable bolt 9, the inner end of which 75 is screwed or otherwise revolvably secured in the wall of part 1. The head of the bolt 9 at its outer end is angular and adapted to receive a proper wrench, as at 10. That part 80 of the head of the bolt which lies in the same plane as the hinge-leaf 8 when pressed against the inner side of the casket is formed as a cam, as at 11, which cam with the turning of the bolt engages the upper side of the 85 hole 8^a in the leaf 8. A lip or flange 12 at the side of the cam prevents the hinge-leaf and the bolt from becoming disengaged when the cam is turned into operative relation with the hole 8.

90 The lid may be secured to the body of the casket in the same manner that the body portion is secured to the bottom, as just described, by means of a series of hinges, having leaves fixed to one part and leaves adapted to engage cam-bolts on the other part, as at 13, Fig. 2, or as illustrated by inverting Figs. 6 and 7. The under side of the marginal piece 4 of the lid is slotted, as at 14, to receive the upper edge of the part 1. In this 95 100

slot and in a groove 15 in the bottom of piece 2, directly beneath the lower edge of the part 1, is placed suitable packing 16. The meeting faces of the panel 6 and the flange 5^a are oppositely grooved, and in these opposed grooves is also a suitable packing 17. The panel 6 is arched upwardly from its side and end margins. To the bottom side of the panel is secured a flat plate 17. In the space 10 between the parts 6 and 17 is disposed the automatic locking mechanism now to be described.

18 18 are two rods running lengthwise of the plate 17 and terminating in bolts 19.

15 These rods are movable longitudinally in guides 20 and are held normally asunder at their adjacent ends by a stout spiral spring 21.

22 22 are bolts disposed at a right angle to the rods 18 and sliding in guides 23. Toggle-pieces 24, pivoted to the bolts 22 and to the rods 18, serve to transmit motion from the rods to these bolts. Bolts 22 and their guides and connections with the rods 18 may be provided at both sides of plate 18; but in practice fixed laterally-projecting lugs 24^a at one side of the plate and movable bolts at the other side will be found sufficient. The bolts 19 22 at their outer extremities are beveled downwardly and backwardly, as at 5, as shown 25 in Fig. 2. Set-screws in the guides 20 for the rods 18, as at 19^a, hold the spring 21 compressed and the several bolts retracted until by the removal of the set-screws these parts are released.

30 35 Pivoted to the bottom of the casket, as at 25, (see Fig. 4,) is a board 26, which may either lie flat upon the bottom or be swung upwardly. On the under side of the board, at its end opposite the pivot or hinge, are 40 notches 27 to receive the upper end of a prop or brace 28, either pivoted on the bottom of the casket or separate therefrom, which prop or brace holds the board 26 at any desired adjustment.

45 50 The operation of my device is as follows: Until the lid is to be finally closed the rods and bolts 18 19 22 are held retracted by set-screws 19^a. The bottom 2 is entirely separated from the body of the casket by turning the cam-bolts 9 out of engagement with the holes 8^a and swinging the hinge-leaves 8 back upon the bottom and beneath the loose drapery or covering. (Not shown in the drawings.) The bottom may now be used as a 55 "cooling-board," thus avoiding the very objectionable practice of the indiscriminate use of the common cooling-board. When the part 2 is thus employed, the elevating-board 26 at the head of the casket may be adjusted 60 as desired, and when raised may be held in place by the brace or prop 28. The body of the casket is slipped into place within the upturned flange 3, the hinge-leaves 8 are swung up against the inner sides and ends of the 65 casket, and the cam-bolts 9 are given a quarter-turn with a suitable wrench. The cams

pressing upwardly upon the hinge-leaves now draw the parts 1 and 2 closely and rigidly together, compressing between them the packing 16, thus forming a tight joint. The action of the screw-thread of bolt 9 also presses the hinge-leaf 8 closely against the part 1, giving additional rigidity to the connection. The manner of detachably securing the lid upon the part 1 and compressing the packing in the channel 15 is the same and will be understood without further description. The panel 6 is the last part to be put into place. To accomplish this, the set-screws 19^a are removed, which permits the spring 21 70 to project the bolts 19 22. The lugs 24 are slipped under the margin of the flange 5^a by 75 tilting the panel and moving it sidewise. The panel is now pressed down into horizontal position, the beveled ends of the bolts being 80 forced back by their contact with the flange 5^a until the margin of the flange is cleared, when the bolts by the pressure of the spring 21 are shot outwardly under the flange 5^a, thus 85 permanently securing the panel in place 90 and locking the casket so securely that to open it will require its destruction. The downward pressure upon the panel 6 necessary to bring it into locked position compresses the packing 17, thus forming a tight joint 95 between the panel and the flange 5^a. It will be seen that the length of the joint between the lid and the panel is so small that it becomes 100 entirely feasible by means of the automatic locking mechanism to form an air-tight and water-tight joint between the two parts.

Having described my invention, what I claim, and desire to secure by Letters Patent, is—

1. In a burial-casket, a body portion, a removable lid having an opening therethrough, means for manually fastening and clamping the lid to the body portion, said means when the lid is in place being accessible only through said opening in the lid, a panel to close said opening, and means for automatically locking the panel to the lid, said automatic locking mechanism being inaccessible when locked in place upon the closed casket.

2. A burial-casket comprising a body portion, a removable bottom, a removable lid having an opening therethrough, normally inaccessible means within the casket for fastening and clamping said bottom and lid to said body portion, said lid fastening, when the lid and bottom are in place, being accessible only through said opening, a panel to close said opening, means for automatically locking the panel to the lid, said automatic locking mechanism being inaccessible when locked in place upon the closed casket.

3. In a burial-casket, a screw-bolt entering the inner vertical wall thereof, an angular head upon said bolt, a flange on said bolt, a cam on said bolt, and a leaf pivotally secured to a horizontal portion of said casket and adapted to engage said cam and flange, in

combination with a packing between said wall and said horizontal portion.

outer ends of said bolts in locked position, and beveled surfaces upon said bolts adapted to 10 slide upon said flange.

4. In a burial-casket, a top, a pair of rods slidably secured lengthwise thereof, a compression-spring interposed between said rods, bolts at the outer ends of said rods, laterally-disposed bolts, connections between said latter bolts and said rods, a flange to engage the

HORACE J. SECOR.

In presence of—

M. D. MERRICK,

L. E. BROWN.
